PAPER DISPENSING OR VENDING MACHINE

Arthur E. Jacobs, Cleveland, Ohio, assignor to
Safe-Guard, Inc., Cleveland, Ohio

Application March 5, 1937, Serial No. 129,270

16 Claims. (Cl. 164—28)

This invention comprises a novel machine for dispensing of paper units or sections in sheet form. In its preferred embodiment the invention is preferably incorporated in a vending machine structure in that the dispensing instrumentalities are conditioned for operation by coin-controlled mechanism. However, while the practical construction of the invention involves novel cooperation of the coin-controlled lock means 10 for the dispensing mechanism, and such forms a feature of the invention, it is within the purview of the invention that the general mechanism used need not include the coin-controlled devices above referred to.

15 In the further carrying out of the invention, it is contemplated that the machine thereof shall be designed especially for dispensing paper sections or units suitable for use as covers for toilet seats to afford sanitary protection.

20 Now it has been proposed heretofore to dispense paper or like seat covers of the general nature for the purpose of those handled in the operation of my dispensing machine, but such machines as have heretofore been put into use 25 comprise magazines in which the seat covers or paper sections are folded, or flat, they being previously cut and disposed in the machine in their folded condition in which they are vended. Machines of this type are of limited capacity because the folded paper sections or seat covers 30 occupy a very considerable amount of space.

Another disadvantage of these prior art devices is the difficulty in loading the magazine properly so that the folded paper sections are 35 perfectly horizontally arranged therein and do not interfere with the action of the horizontally movable dispensing chute usually employed in such devices. The folded paper sections have furthermore, a tendency to expand slightly in a 40 vertical direction within the magazine, which will obviously interfere with the dispensing operations of the chute. The folded paper sections will also swell when subjected to moist atmosphere with similar disadvantages resulting therefrom as above already referred to.

45 In view of the fact that the capacity of the magazine is usually small, a certain amount of folded paper sections must be kept in reserve and the same are usually spoiled and unsanitary. 50 being handled before they are placed in the magazine.

It is therefore the main objective of the present invention to provide a dispensing machine for seat covers or the like which cuts each seat 55 cover individually from a roll of blank supply

paper in a completely sanitary manner, eliminating entirely any undesired handling of the paper to be dispensed. While the arrangement of the supply paper as a continuous sheet in rolled condition permits a considerable increase in dispensing capacity, the dimensions of the machine may be maintained at a minimum, and, especially in view of the fact that the supply paper is wound upon itself, a highly sanitary protection is afforded.

Now, according to my invention, pursuing the objective of providing a machine that will readily dispense or vend seat covers of the class referred to, it is contemplated to provide in my machine a holder for a roll of paper, from which roll the paper is fed in the dispensing operation. Likewise, certain feeding and cutting instrumentalities are resorted to which act upon the paper, in the operation of dispensing the same, for the purpose of cutting out a section of the paper 10 unit that is to form the seat cover, which section will correspond somewhat in size to the opening 15 of the toilet seat on which the cover is to be used. The cutting of the said section of the seat cover to provide a suitable opening therein is effected automatically incident to the feeding of the desired paper section from the machine in the dispensing operation. Likewise, other cutting instrumentalities are employed for cutting 20 off the paper section or unit that is to form the 25 seat cover, in a predetermined length.

The invention as last above outlined therefore 30 comprehends different mechanisms of a novel 35 nature for the feeding of the paper through the machine, for the holding of the paper properly whilst the center section of the paper is being 40 cut from the main body, for maintaining the paper in proper position for the final cutting of the paper section or unit from the roll of paper from which it is fed, and coin-controlled instrumentalities for locking and unlocking the feeding means for the paper when the machine is of the vending machine type requiring the deposit of the coin before the machine is rendered capable of delivering a paper section or seat cover 45 of the class described.

The invention also involves novel detail features of construction other than those above referred to, which will appear more fully as the 50 description proceeds.

In the drawings:

Figure 1 is a front elevation of a coin-controlled dispensing or vending machine embodying the invention.

Figure 2 is an end view looking toward Figure 55

1 from the line 2—2 and in the direction of the arrows in Figure 1, the machine being mounted upon a wall or other support.

Figure 3 is a plan view of the detachable coin box.

Figure 4 is a rear view of the mechanism of the machine with the casing removed.

Figure 5 is a top plan view of the machine with the casing removed and showing the paper roll 10 partially broken away to illustrate certain parts not otherwise visible.

Figure 6 is an end elevation view looking in the direction of the arrows 6—6 of Figure 4, with interior parts shown in dotted lines.

15 Figure 7 is a view similar to Figure 6, but looking in the direction of the arrows 7—7 of Figure 4, and also depicting certain interior parts in dotted lines.

20 Figure 8 is a view in elevation of a supporting plate upon which the rock shaft and detent fingers carried by said rock shaft, are mounted.

25 Figure 9 is a detail view of the tension fingers and pintle rod supporting the same as employed in the construction of the present invention.

30 Figure 10 is a fragmentary vertical sectional view of certain of the guide means for guiding the paper in the process of dispensing from the machine, certain parts of the cutter mechanism including primarily the cutter that finally severs a section of the paper from the strip feeding from the roll, and certain detent parts that hold the paper in the operation of severing above referred to.

35 Figure 11 is a perspective view of a push lever by which the severing cutter device previously referred to is actuated.

40 Figure 12 is a rear elevation of the cutter bar frame and cutter mounted thereon.

Figure 13 is a top view of the device shown in Figure 12.

45 Figure 14 is a vertical sectional view of the cutter bar frame and cutter carried thereby as shown in Figures 12 and 13.

50 Figure 15 is a plan view of the cutter plate and cutter knives carried thereby as laid out in flat form for purposes of illustration only. The view also shows one of the presser plates that coacts with the paper to push the latter away from the cutter plate and knives adjacent thereto as the feed and cutter roll rotates.

55 Figure 16 is a sectional view of the feed roll and cutter plate as illustrated in Figure 15, the latter after being assembled on the feed roll. The view also illustrates certain of the paper presser plates.

60 Figure 17 is a plan view of the seat cover blank or paper section or unit such as will be cut and severed from the roll of paper in the machine in the operation of dispensing or vending one of these seat covers.

65 Figure 18 is a vertical sectional view taken through the operating mechanism of the machine and bringing out more clearly the cooperative interlocking arrangement between the shift lever and feed roll; also showing the coin-controlled lock mechanism for the feed roll; and also illustrating the arrangement of the roll of paper from which the seat covers are severed and dispensed and the manner of guiding the paper through the dispensing slot or opening of the casing.

70 Figure 19 is a sectional view taken approximately on the line 19—19 of Figure 18.

Figure 20 is a fragmentary sectional view taken on the line 20—20 of Figure 18.

Figure 21 is a fragmentary view, partly in elevation and partly in section, of the paper roll as it is mounted upon the tubular shaft support or axis support therefor, and one of the journals which is attached to said axis member or support.

Figure 22 is an end view of the parts shown in Figure 21.

Figure 23 is a perspective view of the coin carrier which forms a part of the coin-controlled lock mechanism.

The machine embodying the invention comprises primarily an outside casing made up largely of a back 1, a curved front plate 2, a bottom plate 3, and a cover or lid member 4 pivoted at 5 to the back 1, said cover 4 curving downwardly at the front where it meets the upper edge of the curved front plate or wall 2 as shown at 6.

20 As seen in Figure 1, which is a front view of the machine, the front plate or wall 2 is provided with a coin opening or slot 7 into which will be introduced an appropriate coin for enabling tripping of the lock mechanism that normally prevents dispensing or vending of articles from the machine when the machine is of the vending mechanism type. Just below the coin slot 7 may be provided an opening 8 for purposes of enabling an indicator means signifying 25 the condition of the machine as full or empty in respect to the supply of articles or paper therein, to be used. Since such means may be of any type known to the art, they are not illustrated in detail.

30 Within the casing comprising the parts previously mentioned is located a frame for supporting the various operating parts of the mechanism of the machine, and this frame generally includes vertical end plates 9 and a front curved cross plate 10 which conforms very closely to the curvature of the front wall or plate 2 of the outside casing, as seen clearly in Figure 18. The curved front plate 10 of the inside frame is rigidly connected with forward rounded extensions 35 of the vertical frame members or plates 9, and constitutes a rigidifying crosswise web intermediate the parts 9, acting additionally as a partial encasing means within the outer casing of the machine feed and cutter roll mechanism later 40 to be described.

Paper supply and feed devices

45 Reference is made to Figure 18 as showing quite clearly that the supply of paper for making the paper articles or seat covers dispensed by my machine is provided with a special structure of supporting axis, preferably in the form of a tubular shaft or axis member 12, which may be made of cardboard. So that paper roll supporting means of only a special nature may be used for the purposes of my dispensing machine, the hollow axis member 12 is provided with metal tubular journal members 13 at its opposite ends, these members being shown best in Figures 21 50 and 22. Each journal member 13 has a slotted inner body dividing said member into a series of tongues 13a, the inner extremities of which are slightly bent outwards to provide penetrating prongs 13b which are adapted to inter-engage 55 in the material of the axis member 12 to interlock the journal member therewith in an obvious manner. The outer end of the journal member 13 is peripherally uninterrupted, or continuous, and when the paper roll 11 is to be disposed in 60

the machine, the lid or cover 4 is raised and the roll 11, with its axis member 12 and journal members 13, are placed in position through the opening normally closed by said cover 4. When in position the journal members 13 rest between a pair of horizontally spaced lugs 14 pressed out from the adjacent end frame member 9 of the inner frame structure, and rest upon pointed bearing members 15 disposed in a plane beneath the lugs 14 and acting as the primary supporting parts for the roll 11. The purpose of using pointed supporting or bearing members 15 which are carried by the frame parts 9 is to prevent the mounting in the casing for use in the machine of a paper roll having wooden or paper axis members such as would usually not work in conjunction with the pointed or supporting bearing members 15.

As seen in Figure 18, the paper, in continuous web form, feeds downwardly from the front portion of the roll 11, past a feed and platen roll 16 and a feed and cutter roll 17, the paper moving between the parts 16 and 17 and passing therefrom downwardly between a guide plate 18 which is disposed in spaced relation to another guide plate 19, both vertically arranged between the frame members 9 and rigidly attached to the latter in any suitable manner. The lower ends of the plates 18 and 19 are substantially coincident with the dispensing opening or slot 20 in the bottom plate 3 of the outer casing.

To facilitate the emplacing in position of the paper roll 11 and the feeding of the paper web therefrom downwardly through the guides 18 and 19, as when replenishing the supply of paper in the machine, it is desirable to move the feed and platen roll 16 rearwardly to afford a free space for passing the paper downward between said roll and the feed and cutter roll 17. For this purpose the roll 16 is mounted in horizontal bearing slots 21 in the frame members 9, the slots 21 receiving the journals 22 of said roll 16. The roll 16 may be shifted horizontally in the slots 21 in which it is supported, said action being accomplished by employing a pair of actuating levers 23, one on each of the frame members 9. Each lever 23 is pivoted at 24 to its associated part 9, and is bifurcated at its lower end as shown at 25, so as to receive in the bifurcation the adjacent journal member 22. The upper ends of the levers 23 terminate near the top of the members 9 and are adapted to be pushed forwardly by a rocker plate 26 pivoted to the members 9 at 27. The rocker plate has downwardly bent actuating arms 28 that engage the rear edges of the levers 23 and have a camming action thereon when the rocker plate 26 is tilted upwardly by means of a handle member 29.

By raising the cover 4 the handle 29 is accessible and may be manually elevated, thereby rocking the cam arms 28 of the rocker member 26 in a forward direction, causing the lower ends of the levers 23 to be shifted rearwardly and thereby carry in a rearward direction in the slots 21, the roll and platen 16. This provides for movement of the member 16 to give the necessary space enabling the paper from the roll 11 to be easily fed downwards between the rolls 16 and 17 into and through the guides 18 and 19 and out through the dispensing openings 20 of the bottom 3 of the main casing.

The feed and cutter roll and platen mechanism

There has been described generally already the feed and cutter roll 17 and the feed and platen

roll 16. The feed and cutter roll 17 is of special construction for the purposes of the invention, and reference is particularly made in this connection to Figures 5, 18, and 19.

For providing the feeding function for the roll 17, it is preferably equipped on its periphery with spaced feeding bands 30 that may be made of soft rubber or any suitable equivalent substance for contact with the paper of the roll 11 in the feeding operation at the same time that the feed 10 and platen roll 16 contacts with such paper, as seen in Figure 18.

Mounted upon the periphery of the roll 17 is a cutter plate, best seen in Figure 15, and designated 31, said cutter plate being equipped with 15 cutters 32 which are symmetrically curved in the manner shown in Figure 15 in respect to their longitudinal dimensions, corresponding ends of the cutters 32 being very closely adjacent as shown at 33, and other corresponding ends of 20 said cutters being widely separated as shown in Figure 15. The cutter plate 31 is curved to conform with the curvature of the roll 17 and is attached to said roll 17 as by means of screws 34 and an angle lug 35 cooperating with the 28 wider end of the cutter plate. The pointed end of the cutter plate is so curved as to be slightly spaced, as shown at 36, from the roll 17, though it is yieldable relatively to the roll by reason of the spring in the metal from which the plate 31 30 is made. Adjacent the wider end of the cutter plate 31 and suitably attached to the roll 17 is a spring presser plate 37, the purpose of which is to act on the paper cut by the cutters 32 to tend to move the paper off or from the cutting edges 35 of said cutters. The plate 37 is well seen in Figure 5, and a similar presser plate, though one of different dimensions, designated 38, is secured to the outer surface of the cutter plate 31 and is normally spring-tensioned away from the cutter 40 plate so as to perform a function like that of the presser plate 37. The plate 38 is situated in the angle adjacent to which the nearer ends of the cutters 32 are disposed.

The cutting edges of the cutters 32 are adapted to work on the periphery or surface of the combined feeding and platen roll 16, which surface may be made of brass or any equivalent material and with which surface also coat the feed bands 30 previously referred to.

In the rotation of the cutter and feed roll 17, by reason of the engagement of the cutters 32 with the platen surface of the roll 16, as the paper from the roll 11 is fed downwardly between the members 16 and 17, the cutters 32 will cut 55 a middle section of the area of the paper in the manner shown in Figure 17. The dimensions of the inner cut section of paper, which is indicated at 39 in Figure 17, will conform somewhat to the size of an opening in a toilet seat, and the section 39 will be so separated from the seat cover unit or section 40 that when the latter is cut off of the strip of paper fed from the roll 11, the user may dispose the seat cover 40 upon a toilet seat with the more pointed end of the 60 section 39 rearwardly arranged, and by pressing down on the section 39 the latter may be depressed into the bowl of a toilet, in an obvious manner. Or, the section 39 may be separated at its front or pointed end from the body of the 65 paper article 40 before placing the seat cover upon the toilet seat, this being quite immaterial to the invention.

It is notable that the levers 23 are held at their upper ends in their rearmost positions by springs 75

23a of somewhat U-form, anchored at their front ends at 23b and attached at their rear ends to studs 23c on the levers.

By having the pointed end of the cutter plate

5 31 spaced, as at 36 in Figure 16, from the roll 17, the accurate cutting of the convergent ends of the cutters 32 of the paper is ensured, even though at the adjacent end portions of the cutters 32 they do not come together but leave a very narrow ligament of the paper, designated 39a in Figure 17, connecting the rear portion of the section 39 to the body of the cover section 40 as long as the paper is passing through the machine and even when it has been dispensed therefrom.

15 *Seat cover or paper section severing mechanism*

As seen in Figures 18 and 19, the feed and cutter roll 17 is supported by an operating shaft 41 equipped with a crank handle 42 at one end thereof. The shaft 41 is operatively connected with the roll 17 by means to be hereinafter described, but for the present it will be understood that upon turning of the crank handle 42 the roll 17 will be revolved, causing corresponding revolutions of the feed and platen roll 16 and feeding downwardly of the web of paper from the supply roll 11. Near the bottom 3 of the main casing and correspondingly near the lower ends of the frame members 9, but supported by the latter, is a cutter frame comprising the vertical end arms 43 and the crosspiece 44, the latter supporting thereon the cutting knife 45, the cutting edge of which is serrated or waved, as seen best in Figure 4. The knife frame 43-44 may be said to be of U-form, therefore, and is rockably supported by a shaft 46 journaled in the frame members 9 at the lower ends thereof.

The roll 17 comprises the peripheral body which has previously been referred to as carrying feed band and cutting appliances, an end plate 17a, and a partition member or plate 17b, the latter disposed intermediate the ends of the roll 17. The shaft 41 passes snugly through openings in the members 17a and 17b of the roll 17 and carries an actuating pin or member 47 arranged to engage in a slot 48 of the partition or disc 17b inside the roll 17, whereby movement of the shaft 41 may be transmitted to the roll 17, as will later be more fully set forth.

50 It being understood that the roll 17 is operable by the shaft 41, it is noted that on the shaft 41 is also mounted an operating cam 49 and said cam is interposed between the end 17a of the roll and the adjacent frame member 9. The cam 49 is interlocked to turn with the roll 17 by means of a stud 50 projecting from the cam through an opening of similar size in the end 17a of the roll 17 and by means of projections 51 bent from the plate which forms the cam member 49 and entering small openings in the end 17a of the roll 17 for completing a proper interlocking of the parts 49 and 17a.

55 The cam 49 is of irregular form, having a cam periphery curved to gradually extend from a point adjacent the center axis or shaft 41 of the cam to a point remote from said axis and near the periphery of the roll 17 as indicated at 49a, whereupon the cam has an abrupt drop or indented slot designated at 49b in Figure 6. The operating edge of the cam 49 is arranged to engage a pin or stud 52 carried by the upper end of an actuating lever 53 of somewhat S-form, see Figure 6, which stud 52 passes through a slot 54 in the adjacent frame member 9 of the machine. The lever 53 is pivoted by means of a knife frame axis

shaft previously referred to, constituting the axis for said lever, and the said lever is also of somewhat S-form in side elevation, the lower end of the lever constituting its axis portion. At the intermediate curved portion of the lever 53, the 5 same is provided with an opening 53a engaging the pin 53b on the cutter bar 43, said pin passing through a slot 55 in the lower portion of the frame member 9 and connecting the lever 53 to one of the end arms 43 of the knife frame 43-44. 10 The lever 53 being on the outside of the adjacent frame member 9 requires the employment of the pin 53a and slot 55 in order to establish the connection between the lever and the knife frame which is situated at the inner sides of the members 9.

From the foregoing it will be understood that when the shaft 41 and the cam 49 are rotated, the cam portion of the cam 49 engages the stud 52 and rocks the lever 53 rearwardly at its upper 20 portion toward the back 1 of the casing. Obviously, such movement through the intermediary of the pin 53b will tend to force the knife frame 43-44 rearwardly also.

Carried by the shaft 46, see Figure 4, is a coil 25 spring 56 which possesses considerable tension and acts as a motor spring, one end thereof being anchored at 57 to the shaft 46 and its opposite end being engaged as shown at 58 with an adjacent lug 59 on a kick-off lever 60. The kick-off 30 lever 60 is made up of a plate having spaced bearings 61 receiving the shaft 46, the plate being formed with the lever extension 62 adapted to engage the pin 53b previously referred to as outstanding from the adjacent arm 43 of the knife 35 frame, said pin passing through the slot 55 to connect with the actuating lever 53. The tension of the spring 56 is maintained by a pin 56a mounted within an opening of shaft 46 and bearing against a crossbar 46b arranged between the 40 frame members 9.

The normal tension of the spring 56 is to maintain a strong spring pressure forwardly upon the kick-off lever 60 to cause the latter, by its lever arm 62, to engage and kick forward the 45 knife frame for the knife 45 when the cam 49 has been revolved sufficiently to permit the stud 52 to pass off the peripheral cam edge of the cam and enter the drop slot or indent 49b of the cam. The lever 60 is therefore not positively connected 50 to the knife frame but is adapted to force the knife frame outwardly toward the paper strip fed down from the supply roll 11 with a kick action after the tension of the spring 56 has been increased by the pushing rearwardly of the lever 53 55 and knife frame 43 under the action of the cam and against the pressure of spring 56. This kick-off action to impart the cutting or severing movement to the knife 45 takes place approximately at the end of a revolution of the feed and cutter 60 roll 17. A stop 64 limits the forward movement of the kick-off lever 60 after it has kicked off and acted upon the knife frame 43-44, which is free to move forwardly slightly beyond the range of movement of the member 62 of lever 60 by the 65 inertia created by the push or kick action given to the knife frame by the member 60 in the above operation.

At the end of the knife frame 43-44 opposite that adjacent to which the spring 56 and the 70 kick-off lever 60 are located, is a spring comprising the horizontal portion 65 and the vertical portion 66, see Figure 7, the part 66 of the spring bearing against a pin 67 standing out from the arm 43 of the knife frame at the right-hand 75

side of the machine. The action of the spring part 66 is to tend to throw the knife frame rearwardly under relatively light tension action of the spring to maintain the stud 53a in normal contact with the lever arm 62 of the lever 60. The tension of the spring 65-66 is not sufficient, however, to prevent the final kicking forward of the knife 45 by the action of the kick-off lever 60-62 at the end of the movement or rotation 10 of the roll 11 for the dispensing of a paper section or cover member such as described. It is this final kick forward movement of the knife 45 from the position shown in Figure 18 to a point intersecting the path of movement of the paper fed downwardly from the roll 11 that severs the paper section to be dispensed as a unit, from the main web of paper, the line of severance being horizontal because of the disposition of the knife 45 and its relatively horizontal cutting edge.

20 *Paper tension control mechanism*

It will be apparent that if the cutting action of the knife 45 is to be efficiently performed, it is desirable to use some means whereby the paper feeding downwardly from the roll 11 may be held or tensioned slightly between the roll 11 and the guides 18 and 19 at a point below the knife 45. In other words, it is desirable that slight tautness be maintained on the paper below the knife 45 as well as above it during the cutting action of the knife 45, to provide for clean severing of the paper in the section or cover member to be dispensed. The instrumentalities for this purpose will now be described.

35 Reference has been made to the pin 67 at the right-hand side of the machine and cooperating with the spring parts 65-66. This same pin 67, carried by the right-hand arm of the knife frame 43-44, passes through a slot 68, see Figure 7, in the right-hand frame member 9, the terms right and left as used herein to be used as looking in a direction from the front of the machine. On the outside of the right-hand frame member 9 and connected at one end to the pin 67 is a link 45 69 that connects the pin 67, and thus the knife frame 43-44, with a rocker arm 70 on a rock shaft 71. The rock shaft 71 carries a number of tension fingers 72 located at intervals throughout its length across the entire machine. These 50 tension fingers 72, see Figure 10, are adapted to be rocked from the dotted line position of Figure 7 to the full line position of Figure 10, to thereby shift the fingers 72 into engagement with spring fingers 73 carried by a pintle rod 74, the ends 55 of which are mounted in bearings on the guide plate 18. The fingers 72 are relatively rigid respecting the shaft 71 and the shaft 71 has its ends mounted in bearings in the members 9. The tension fingers 73, however, are light spring fingers 60 supported by the pintle rod 74 on the guide member 18. The guide member 18, as seen in Figure 8, is formed with openings 18a, one for each of the fingers 73, and correspondingly one for each of 65 the actuating fingers 72, so that when the shaft 71 is rocked by movement of the knife frame 43-44 the relatively rigid fingers 72 will move rearwardly, see Figure 10, to an approximately horizontal position, and, passing through the 70 openings 18a, will bear against the light spring fingers 73 to thereby cause the fingers 73 to press against the wall of the guide plate 19 which is opposite the guide plate 18. When this pressing action takes place, the fingers 73 press against 75 the paper that is pushed between the guides 18

and 19 as it passes down to the dispensing opening 20.

The mechanical operation of moving the fingers 72 to cause them to coact with the fingers 73 and effect contacting of the latter with the paper web passing down from the roll 11 is timed to take place just before and while the knife 45 performs its cutting operation. It will be borne in mind that the knife frame 43-44 is actuated from the roll 11, and the parts 72 and 73 are likewise actuated indirectly from the roll 11 through the knife frame, and the actions of the cutting and tensioning of the paper are coordinated so that the paper web will be tensioned when the knife 45 severs the paper unit or section that will form the seat cover, from the web fed from the roll 11, the severance line being below the contacting portions of the feed and cutter roll 11 and the feed and platen roll 16. In other words, while the paper is being cut, it is, practically speaking, held taut by the friction of the rolls 16 and 17 above the knife and the pressure between the parts 19 and 73 located below the knife.

As a simple means for holding the spring 25 fingers 73 normally out of contact with the paper strip so as not to interfere with the free downward feed of the latter from the rolls 16 and 17, before the time for cutting arrives, a spring plate 75 is fixed to the front side of the guide 30 member 18 near the left end of the latter, and the upper portion of said plate has a T-shaped part 75a, the ends of the side arms of which engage beneath two of the fingers 73. The action of the part 75a is to normally bear outward 35 upon the two fingers 73 with which it coacts to rock the pintle rod 74 in an outward direction from the member 18 to thereby cause all of the spring fingers 73 to remain in the positions in which they are shown in Figure 18. Of course 40 the pressure of the more rigid fingers 72 at the proper time overcomes the resilient force of the member 75 respecting its coaction with the parts 73 and 74.

45 *Coin-controlled lock mechanism*

Referring now to Figures 1, 18, 19, and 20 particularly, it is notable that the coin-controlled devices by which the feed roll parts are normally prevented from being operated until a coin is introduced into the machine at the proper place, are located primarily at the right-hand end of the feed and cutter roll 17. As seen in Figures 19 and 20, the right-hand end of this roll 17 is open, practically speaking, and provides a compartment at the right side of the partition or disc 17b within said roll. The said compartment receives a cylindrical extension 76 that projects inwardly from the right-hand frame member 9 and forms a coin chamber 77. Of course the extension 76 is stationary with the right-hand frame member 9, and the latter, as seen in Figure 19, is cut away at 78 to provide a semi-circular shaped opening through which may slide a semi-circular shaped drawer 79. 65 The drawer 79 is provided with key-actuated lock mechanism designated generally A, with which is used a key 80, and said lock mechanism includes a tumbler controlled arm 81 movable to and from a position engaged with the inner side 70 of the frame member 9 at the right of the machine, see Figure 19. Any suitable key-controlled lock mechanism A may be resorted to for engaging and disengaging the arm 81, whereby the drawer 79 will be locked from displacement or 75

permitted to be removed, the latter to enable the money received in the drawer 79 to be taken away.

I shall now proceed to describe the manner in 5 which the roll 17 is locked normally from operation and released by introducing a coin into the coin slot 7 for cooperation with proper mechanism by which unlocking of the roll and dispensing operation of the entire machine may be 10 caused.

At its right-hand end the roll 17 has a detent flange 17c provided with a notch 17d therein, the upper wall of the notch as seen in Figure 18 being abrupt and the lower wall curving to the 15 periphery of the flange 17c. A coin-controlled lock lever 82 is pivoted at 83 above the roll 17 and has a lock arm equipped with a lock lug 84. A spring 85 normally engages the lock lug 84 20 to hold the latter in contact with the flange 17c and to cause the lug to enter the notch 17d to prevent turning of the roll 17 in a clockwise direction as seen in Figure 18.

Reverse movement of the forward and cutter roll 17 by the crank handle 42, or otherwise, is 25 prevented by means of a lock pawl 86 carried by the curved front wall 2 of the inner supporting frame, said lock pawl coacting with openings 87 at intervals in the periphery of the roll 17 so as to permit the roll to turn in a clockwise direction 30 as seen in Figure 18, but prevent it from being reversely moved by means of the crank handle 42.

Already there has been described the connection of the shaft 41 to the roll 17 by means of the pin 47 which engages in the slot or opening 48 in the partition or disc 17b which is fixed to the roll 17. The opening or slot 48 in the partition 17b is of slightly greater area than the pin 47 so that the shaft 41 may be moved by the crank 40 handle 42 while the roll 17 is locked by the lock lever 82 and part 84 against any movement. The purpose of this loose connection established by the parts 47 and 48 is to permit of an initial 45 movement of the shaft 41 by the handle 42 to cause the actuation of certain parts receiving a coin, whereby the coin is shifted to unlock the roll 17 from the lock lug 84 cooperation. The coin moving and actuated parts will now be set forth. In Figure 19 it will be observed that a 50 shift lever 88 is positioned alongside of and in contact with the partition 17b of the roll 17. The shift lever has an axis portion surrounding the shaft and is formed with an opening or slot radial from the axis opening in which the pin 55 47 previously referred to is disposed. The opening in the axis portion of the shift lever 88 receiving the pin 47 is of substantially the same size as said pin, as distinguished from the larger opening 48 in the partition 17b and previously 60 described. For interlocking or connecting the shift lever 88 loosely with the partition 17b, projections 89 extend from the partition and pass through curved slots 90 in the shift lever, the slots being longer than the projections 89. It 65 will thus be seen that the lever 88 is capable of turning slightly relatively to the roll 17, and, because the projection 47 snugly engages the slot of the lever receiving same, the initial and subsequent movements of the shaft 41 by the 70 handle 42 will always impart direct and immediate movement to the interlocked lever 88. The lever 88 is equipped with opposed lateral arms 91 seen in section in Figure 18, which arms receive therebetween the inwardly extending coin 75 supporting member 92 of the coin carrier 93,

see Figure 23, which latter is mounted to slide on the periphery of the roll 17. The sliding connection between the carrier 93 and the roll 17 is established by pins 94 extending from the ends of the carrier 93 and entering slots 95 in the periphery of the roll 17. Normally the coin carrier 93 is held so that the pins 94 are in the left-hand ends of the slots 95 by means of a coil spring 96, see Figure 18, said spring being connected to one of the arms 91 of the shift 10 lever 88.

A coin designated in Figure 18 at 97, when inserted through the coin slot 7 of the front plate 2 of the casing, will be received by the coin holding member 92 of the carrier 93 and supported by the periphery of the cylindrical extension 76, as shown. This coin is thus supported in a path of movement intersecting an actuating abutment 98 which is carried by the arm 99 of the lock lever 82 for the roll 17. The upper wall of the cylindrical extension 76 forming the coin compartment is formed with a coin slot or opening 100 adjacent to the coin-entering opening 7 in the casing but laterally spaced from the latter.

With the construction of parts as just described, the action of the handle 42 and shaft 41 in relation to the coin actuated mechanism is as follows:

We will assume that a coin 97 has been placed in position on the coin carrier 93 through the coin slot 7 as shown in Figure 18. The operator grasps the handle 42, not being able to turn the same in a reverse or counter-clockwise direction as seen in Figure 2, and must turn it to the right. This clockwise movement of the handle 42 is 35 imparted to the shaft 41 and the first action resulting is that the shift lever 88 is turned slightly by the pin 47 because of the snug fit of said pin in the slot adjacent the periphery of the shift lever. The roll 17 at this time is stationary and 40 the shift lever rotates to the right, carrying with it the coin carrier 93 and the coin 97 disposed therein. The abutment 98 and cam 101 are 45 in the path of this movement of the coin and are engaged by the coin, the latter acting with camming effect and forcing downward the abutment so as to actuate the lever 82 in a manner to raise the lock lug 84 out of the notch 17d of the flange 17c of the roll 17. This unlocking of the roll 17 by the movement of the lever 82 takes place 50 before the pin 47 contacts with the right-hand wall of the slot 48 in the partition 17b, and the shifting of the lever 88 of course moves the carrier 93 upon the roll 17 and relatively thereto increasing the tension of the spring 96 while the roll 17 is stationary. As soon as the coin has 55 acted upon the abutment 98 in the manner stated, it drops through the slot or opening 100 in the cylindrical extension 76 and passes downwards into the coin box 79. In the meantime the roll 17 has been released because the lock lug 84 60 has been raised out of the notch 17d and is able to travel on the periphery of the flange 17c. The turning movement of the shaft 41 having initially moved the lever 88 and brought the pin 65 47 into engagement with the right-hand wall of the slot 48, the continued movement of the shaft by the handle 42 rotates the roll 17 so that the latter may perform its feeding and cutting operation on the strip of paper passing downwardly 70 from the supply roll 11. The shaft 41 is caused to make a complete revolution, such degree of movement causing to be fed from the machine and properly severed, one of the paper sections or seat covers previously described. When said 75

revolution of the shaft 41, shifting lever 88, and roll 17, has been completed, the lock lug 84 drops back into the notch 17b and prevents another operation or revolution of the roll 17 until a fresh 5 coin is placed in the coin carrier.

Of course, when the roll 17 is restored to its normal position of Figure 18, after a revolution thereof, and locked, the spring 96 restores the coin carrier 93 to its normal position with the 10 member 92 below or opposite the coin opening 7. During the initial movement of the lever 88 relatively to the roll 17, the slotted portions 90 of the lever move relatively to the projections 89.

On the cover 4 of the outer casing is a spring 15 pressure plate 102 that bears on the paper roll 11 when the cover is closed to thus prevent overrunning of the roll as paper is fed therefrom.

Complete operation of machine

20 Assuming that the machine is empty and it is desired to place in position a roll of paper from which the paper sections or seat covers to be dispensed from the machine are to be made,—the lid 4 is raised, and this renders the handle 29 accessible and it is elevated to rock the member 26 and cam to the left as seen in Figure 18 the upper ends of the levers 23. The roll of paper 11 with an axis member 12 and the journal members 13 applied thereto is then dropped into the space 30 between the bearing projections 14 on the members 9 and the journals 13 are supported by the pointed bearing parts 15. The web of paper of the roll 11 is passed downwardly between the rolls 16 and 17, the roll 16 having been shifted rearwardly by the operation of the handle 29.

35 Or, if desired, the paper web may be fed between the rolls 15 and 17 before emplacing the roll 11 in position upon the supporting means therefor. The web of paper from the roll 11 is at this time fed downwardly through the slot 20 at the bottom 3 of the casing by being passed between the guides 18 and 19. It will be assumed that the roll 17 is locked by the normal adjustment of the positions of the parts.

40 It being desired to vend a paper section or seat cover from the machine, a coin 97 is introduced through the slot 7 into cooperation with the coin carrier 93. The handle 42 is now turned clockwise as seen in Figure 2, and at once the cam 49 commences to act upon the S-lever 53, see Figure 6, to rock the knife frame 43—44 rearwardly as seen in Figure 18, the tension of the spring 56 being increased by the action of one side arm of the knife frame upon the lever 60.

45 As the knife frame 43—44 is moved rearwardly, preparing the knife 45 for being kicked off to perform its severing function, the paper is feeding down from the roll 11 between the platen roll 16 and the feed and cutting roll 17. At the same time the paper is being cut by the cutter parts 32 on the cutter roll 17. Additionally, while the knife frame 43—44 is being acted upon through the operation of the cam 49, motion is communicated from said frame to the shaft 71 and actuating fingers 72 for moving the parts 72 upwardly toward and into engagement with the spring fingers 73 so that when the pin 52 rides off the cam periphery of the cam 49 into the slot 49b thereof, the spring fingers 73 will have been 50 caused to engage the paper and at the same time as this takes place the kick-off lever 60, by the power stored up in the spring 56, will have kicked the knife 45 forwardly, see Figure 18, and thus sever the paper section, which may be used 55 for the seat cover, from the main web of paper.

of the roll 11 at a point below the contacting feed and cutting roll 17 and feed and platen roll 16.

The operation of the coin 97 in being first shifted by the shift lever 88 and coin carrier 93 to depress the abutment 98 and unlock the roll 17, 5 before said roll starts to move to feed the paper downwards to the spring detents 73 and knife 45, has already been described. The shift lever 88 moves first with the coin carrier 93 to rock the lever 82 and raise the lug 84. Then the shaft 41, 10 which has moved the shift lever 88, picks up the roll 17 and rotates the latter to cause the feeding and cutting action of the paper as described. When the coin has passed the abutment 98, it falls down into the coin compartment and coin box 79 15 through the opening 100 in the extension 76.

When the roll 17 completes a revolution, it is re-locked by the member 84 of lock lever 82 and a coin 97 must be introduced into the machine to cause a subsequent operation or vending of a 20 paper section or seat cover as described.

It is to be understood that if desired that the machine be used, not as a vending machine, but as a mere dispensing machine, the coin-controlled mechanism set forth may be omitted.

25 The resilient mounting of the plate 31 and blades 32 in the vicinity of the pointed portion of plate 31 assures a perfect cutting function of the blades 32 at their ends near the space 33 even though the roll 17 and platen roll 16 are somewhat 30 disaligned with respect to their horizontal axes.

Having thus described my invention, what I claim as new and desire to secure by Letters Patent of the United States, is—

1. In a paper dispensing machine, in combination, a support for paper to be dispensed, a feed and cutting device adapted to feed paper through the machine, a platen, a cutter carried by the feed and cutting device and cooperative with said platen to cut the paper within the area thereof as it is fed through the machine, yieldable means 35 carried by the feed and cutting devices and engageable with the paper as it is fed thereby to move the paper away from the cutter after cutting, and means for severing a section of the paper so cut as it is fed from the machine by said device.

2. In a paper dispensing machine, in combination, a frame, supporting means for a roll of paper carried by said frame, a feed and cutting roll comprising feed and cutting members carried thereby, a platen associated with the feed and cutting roll and cooperating with the cutting means of the latter, and operating means for one of the platen and roll parts for shifting the same 50 away to space said parts and facilitate passage of a paper web therebetween preliminary to feeding operation of the latter.

3. A paper dispensing machine as claimed in claim 2, in which the operating means comprises levers coacting with the platen, means for moving said levers to shift the platen as stated, and means for restoring the levers to a position in which the platen assumes a position for cooperation with the feed and cutting roll.

4. In a paper dispensing machine, a frame, a support therein for a roll of paper to be dispensed by the machine, feed roll mechanism for feeding paper from the machine, actuating means for said mechanism, a knife movable towards and 55 away from the path of the paper for cutting the paper in a predetermined length from the paper supplied from the said paper roll, and means for actuating said knife from the said actuating means, said last named means including means 60

for normally tensioning said knife away from the path of said paper, and means for storing energy in said knife and quickly releasing the same in an amount sufficient to overcome the tension aforesaid, whereby to cause the knife to move towards and sever the paper.

5. In a paper dispensing machine, in combination, a frame, a support thereon for a roll of paper, feed roll mechanism carried by the frame and comprising a feed and cutting roll, cutting members on the feed roll to cut the paper as it travels, operating means for said feed roll mechanism, a cutting knife pivotally mounted in said frame on an axis displaced from the axis of said feed roll mechanism for cutting the paper in a predetermined length as it is fed from the machine, and connections between the said cutting knife and the operating means for the feed roll mechanism for actuating the knife to cause it to perform its cutting function after the feed roll mechanism has fed a predetermined length of paper beyond said knife.

6. In a paper dispensing machine, in combination, a frame, a support thereon for a roll of paper, feed roll mechanism carried by the frame and comprising a feed and cutting roll, cutting members on the feed roll to cut the paper as it travels, operating means for said feed roll mechanism, a cutting knife for cutting the paper in a predetermined length as it is fed from the machine, connections between the said cutting knife and the operating means for the feed roll mechanism for actuating the knife to cause it to perform its cutting function after the feed roll mechanism has fed a predetermined length of paper beyond said knife, and paper engaging members operated incident to the operation of the feed roll mechanism for engaging the paper adjacent to the knife and holding the paper at such point while the knife acts thereon.

7. In a paper dispensing machine, in combination, a frame, supporting means on the frame for a paper roll from which paper is dispensed through the machine, feed roll mechanism arranged to coat with the paper supplied from said roll, a cutting knife adapted to cut the paper in a predetermined length while the paper is being held at one point by the feed roll mechanism, paper engaging means for holding the paper as the cutting knife is caused to cut the same, connections between the feed roll mechanism and said cutting knife and paper engaging means so that the latter are operated incident to the operation of the feed roll mechanism, and operating means for the feed roll mechanism.

55. 8. A paper dispensing machine as set forth in claim 7, wherein the knife is arranged between the point of engagement with the paper of the feed roll mechanism and the point of engagement with the paper of said paper engaging means, so that the paper is held relatively taut by the feed roll mechanism and said paper engaging means when the knife acts to cut the paper.

9. In a paper dispensing machine, in combination, a frame, a support, means carried by the frame for a roll of paper from which paper is to be dispensed through the machine, a feed roll mechanism adapted to engage and feed the paper through the machine, operating means for said feed roll mechanism, a movable cutting knife arranged to operate in a plane intersecting the plane of movement of the paper to sever the same in a predetermined length, paper engaging fingers movable into contact with the paper, a guide member for the paper cooperating with said paper

engaging fingers so that the latter frictionally engage the paper and hold it temporarily when the fingers are operated, and instrumentalities connecting said paper engaging fingers and the cutting knife with the feed roll mechanism for actuating the fingers and the said knife incident to the operation of the feed roll mechanism.

10. In a paper dispensing machine, in combination, a supporting frame, a paper roll support means carried thereby, feed and cutting roll mechanism carried by said frame and comprising a movable platen and a feed and cutting roll associated with the platen, paper feeding members on the feed and cutting roll coating with the platen to feed paper between the two rolls, cutting members on the feed and cutting roll cooperating with the platen to cut paper fed between the two rolls, paper engaging means spaced from the point where the paper roll mechanism engages the paper, means for actuating said paper engaging means from the feed and cutting roll mechanism, and a knife also operated from the feed and cutting roll mechanism and arranged to sever the paper at a predetermined point as it progresses through the machine, said knife operating at a point between the point where the feed and cutting roll mechanism coats with the paper and the point where the paper engaging means coats with the paper, and a guide member for the paper cooperating with the paper engaging means.

11. In a paper dispensing machine, in combination, a frame, a support in said frame for a supply of paper, feed roll mechanism for feeding said paper through the machine, said mechanism comprising a main feed roll, an operating device for said main feed roll, a platen roll, means for shifting the platen roll bodily away from the feed roll, guide means for the paper fed from the feed roll mechanism, paper engaging detent means cooperating with said guide means, connections between the operating means for the main feed roll and said paper engaging detent means to actuate the latter, and a cutting knife operated from the feed roll mechanism and disposed between the point where the main feed and platen rolls cooperate with the paper and the point where the paper engaging detent means engages the paper so as to sever the paper intermediate said parts while it is held therebetween.

12. In a paper dispensing machine, in combination, a support for a supply of paper, feed roll mechanism comprising a main feed roll, a platen roll coating with said main roll, a guide for the paper, paper engaging members cooperative with the paper to press it against the guide and hold it at such point, devices for actuating said paper engaging members, a shaft for operating the main feed roll, instrumentalities connecting said shaft with said devices that operate the paper engaging members, a cutting knife for severing the paper of a predetermined length, and operating means for said cutting knife connected with the shaft of the main feed roll for actuation thereby.

13. A paper dispensing machine as set forth in claim 12, combined with feed bands on the feed roll coating with the platen roll for feeding action on the paper passing between the rolls, and cutting members applied to the periphery of the main feed roll and coating with the platen roll for cutting the paper as it passes between the main and platen rolls.

14. In a paper dispensing machine, in combi- 75

nation, a frame, a support therein for a supply of paper, a main feed roll, a platen roll coacting with said feed roll, a shaft supporting the main feed roll, a cam connected with said shaft, a cutting knife for severing the paper after it has passed between the feed rolls a certain distance, and actuating connections between the said cam and the cutting knife for operating the latter.

5. In a paper dispensing machine, in combination, a frame, a support therein for a supply of paper, a main feed roll, a platen roll coacting with said feed roll, a shaft supporting the main feed roll, a cam connected with said shaft, a cutting knife for severing the paper after it has passed between the feed rolls a certain distance,

actuating connections between the said cam and the cutting knife for operating the latter, paper engaging fingers, a guide member spaced from said fingers and adapted to cooperate therewith when the fingers are adapted to press paper against the guide member, and actuating connections between the said fingers and the said cam whereby operation of the cam incident to movement of the main feed roll will cause actuation of said paper engaging fingers.

16. A paper roll support means comprising an axis member, journal members of a hard substance applied thereto, and pointed bearings supporting the said journal members.

ARTHUR E. JACOBS. 15
